UNITED STATES PATENT OFFICE

ERNEST STULIK, OF BUFFALO, NEW YORK

DESIGN FOR A DISPLAY STAND

Application filed March 25, 1932. Serial No. 43,285. Term of patent 3½ years.

To all whom it may concern:

Be it known that I, ERNEST STULIK, a citizen of the United States, residing at Buffalo, in the county of Erie and State of New York, have invented a new and original Design for Display Stands, of which the following is a specification, reference being had to the accompanying drawings, forming a part thereof.

stand embodying my design. Figure 2 is a similar view but taken at approximately forty-five degrees from the position shown in Figure 1. Figure 3 is a top plan view of the display stand.

I claim:

The ornamental design for a display stand, substantially as shown.

ERNEST STULIK.
